WALDO SHELDON, OF SOUTH NORWALK, CONNECTICUT

WELL-DRILL ROTARY TABLE

Application filed February 3, 1925. Serial No. 6,535.

This invention relates particularly to deep oil well drilling by the methods disclosed in my co-pending patent applications and involving the use of power mechanism for effecting a regulatable positive feed and control of the drill.

Under certain conditions it has been found desirable to change from the positive pressure feed back to the ordinary rotary process of drilling and the general objects of this invention are to provide a simple and practical way of making this change from pressure feed to ordinary rotary drilling or vice versa without complicating or encumbering the machine.

One form of the invention by which these objects are attained is illustrated in the accompanying drawings, but as the structure is susceptible of modification without departure from the broad spirit and scope of the invention, it should be understood that these drawings are primarily for illustrative purposes and that the invention is not necessarily confined to this particular form of structure.

Figure 1 is a vertical sectional view showing an application of the invention to one of the hydraulic pressure feed drills invented by me and in use for driving a special fluted grief stem.

Figure 2 is a cross sectional view on substantially the plane of line 2—2 of Figure 1, showing the interlocking sliding driving engagement between the collet clutch and grief stem.

Figure 3 is a plan view illustrating particularly the two-part hold-down bar for securing the collet in its seat.

Figure 4 is a sectional detail of the hold-down bar on substantially the plane of line 4—4 of Figure 3.

Figure 5 is a vertical sectional view showing application of the collet to the driving of smooth drill stem.

Figure 6 is a cross sectional view of these parts on substantially the plane of line 6—6 of Figure 5.

Figure 7 is a sectional detail illustrating the jointed structure of the grief stem.

Figures 8 and 9 are sectional views of a modification of the driving engagement between the chuck and grief stem, Figure 8 be-

ing a cross sectional view of the grief stem as on the line 8—8 of Figure 9 and showing a portion of the cooperating collet.

Figure 10 is a view of the complete apparatus on a reduced scale showing the hydraulic feed cylinder.

In Figure 1 only enough of the drill is shown to illustrate application of the present invention thereto. Thus only a portion of the rotary table is shown at 10, the same carrying a key or keys 11 engaging in a way or ways 12 in the chuck sleeve 13. This chuck sleeve is raised and lowered in the table by a hydraulic piston, a portion of which is indicated at 14. This piston carries upper and lower bearings for the chuck sleeve, the upper one of which is indicated at 15. Fixed to the chuck sleeve is an adapter socket 16 which carries a bushing 17 for the chuck collet 18.

This clutch collet is also shown as generally similar in construction to that disclosed in my companion application, Serial #736,206, that is, with a compressible conical lower portion 19 fitting the taper of the socket bushing 17 and having a head portion with outstanding lugs 20, engaged in key sockets 21 in the adapter and springs 22 being engaged beneath such lugs to lift the collet when the pressure of the clamp bar is released. Similarly, the collet is shown as made in two sections, 18^a and 18^b, Figure 2, so that the collet may be removed and replaced in sections at opposite sides of the drill rod or grief stem. These sections of the collet may be split longitudinally as indicated at 45 as in the application referred to, to add further to the yielding or spring gripping characteristics of the collet.

To enable the collet to handle round drill pipe or fluted grief stem, the inside of the collet is for the most part made up of a substantially cylindrical gripping surface 23 to grip cylindrical pipe while driving engagement with the grief stem is effected by longitudinally grooving the bore of the collet at 24 to receive the ribs or shoulders 25 on the fluted portion of the grief stem 26.

In Figures 1, 2 and 3, the meshing shoulders or ribs and grooves of the stem and collet are sharply angled but the same results may

be attained with less expensive machining by simply forming the grief stem with two flattened sides, as shown at 27, in Figures 8 and 9, to leave lesser angled ribs 28 for sliding engagement in correspondingly grooved portions 29 of the collet. This latter structure leaves the collet with cylindrical portions at 30 to grip the round drill pipe.

To enable the use of an extended line of grief stem, the same may be made in a plurality of jointed sections suitably connected in end to end relation as by screw joints indicated at 31. At the adjoining ends these sections are shown as left plain or cylindrical at 32, so that if the drive shoulders on connected sections do not come into register when the sections are screwed together, the clutch sleeve may be raised or lowered to bring the collet over the round portion, then rotated by turning the table to register the shoulders in the collet with the shoulders of the added grief stem section and the chuck lowered or raised to couple the clutch in sliding engagement with the new grief stem section. If it should be necessary for any reason to grip this intermediate smooth portion of the grief stem, the same can be accomplished by setting the collet down in its socket until the cylindrical portions of the same effect a gripping engagement with the rounded portion of the grief stem.

The collet is shown held to its seat in the adapter by a clamp made in two bar sections 33, 34 having transversely slotted ends 35, 36, to pass from opposite sides about the bolts 37, which bolts are fixed in the head of the drill driving sleeve 13, said bar sections being transversely recessed in their intermediate portions at 38 to clear the drill pipe or grief stem. The first section 33 is shown as having an extended edge portion 39 overlapping a correspondingly extended edge portion 40 on the opposite section 34, and the slotted ends of the two sections are similarly overlapped, except that as shown in Figure 4, the meeting faces of these parts are reversely angled as indicated by the plane 41 so that in turning down the clamp nuts 42, the effect of the meeting inclines will be to crowd the sections together and automatically lock them in holding relation. It will be obvious that the tightening of these nuts will set the collet in gripping engagement with a smooth drill pipe and that upon turning back these nuts, the collet springs will lift the collet sections to release the drill pipe. In driving the grief stem the collet is adjusted so that the grief stem will slide freely therethrough, thus enabling operation of the drill as a straight rotary.

The change from rotary to pressure feed operation may be made at any time to meet different drilling requirements, or conditions, without changing the collet other than simply adjusting it to grip the smooth drill pipe

which is substituted for the grief stem so that the force of the hydraulic cylinder will be applied to the drill stem and the drilling then be effected under regulatable pressure feed, as shown in Sheldon Patent 1,681,501 of Aug. 21, 1928, and indicated generally in Figure 10 herein, where 43 illustrates the annular hydraulic cylinder in which the annular piston 14 operates to apply force to the drill driving sleeve 13.

When drilling with the smooth pipe at great depths or under heavy pressure, there is a tendency for the collet to slip over the smooth drill stem unless it be set very tight in its contracting socket. A special feature of this invention is the overcoming of this slippage tendency by providing on the inner gripping surfaces of the collet, a screw thread such as indicated at 44 having a right handed pitch so that just as soon as the collet starts to slip, it will cut or form a companion screw thread in the pipe and thus screw itself down over the pipe, thereby automatically seating itself deeper in the contracting socket and so, further contracting upon the pipe and increasing the grip sufficiently to overcome the slippage.

This automatic self-threading and grip increasing action may take place at any time when slippage starts. The collet or the screw threaded portion of the same is sufficiently hardened to operate in the manner described. The screw thread may be substantially continuous about the inside of the collet, except for the interruptions provided at the grooves which receive the shoulders of the grief stem and which interruptions actually increase the effectiveness of the screw thread cutting or rolling action. The screw threads may extend the full length or only part length of the collet and may have an upward taper as shown to increase the "crowding" effect.

In the operation of the invention for straight rotary drilling, when the grief stem slides freely through the chuck, special means may be provided to prevent the chuck collet being closed down in gripping engagement with the stem. Means for this purpose are illustrated in Figure 1 in the form of a block 46 slipped into position beneath the head of the collet, thus limiting the downward movement of the collet in its socket and hence the extent to which it can be closed.

In the present disclosure, the screw threads of the collet are shown as having a flat upper side providing a certain amount of "relief" in the screw cutting action, but it will be understood that the shape may vary. Instead of being tapered toward the upper end, the bore of the collet may be of the same diameter throughout. Other variations and changes may be made in the structure without departure from the spirit and scope of the invention as the invention is claimed broadly.

What is claimed is:

1. As an article of manufacture, a drill stem drive collet having a cylindrical passage therethrough grooved to receive the ribs or corners of a grief stem, said collet being made of spring material and slotted to divide the same into resilient sections. 70
2. In well drilling apparatus, a drive socket, a drill rod clamp seated in said socket having cylindrical portions for driving engagement with drill rod and grooved for the passage of the ribs or corners of a grief stem and means for securing said clamp in the socket adjustably engaged either with drill rod or with a grief stem. 75
3. In well drilling apparatus, a drive socket, a drill rod clamp seated in said socket having cylindrical portions for driving engagement with drill rod and grooved for the passage of the ribs or corners of a grief stem and means for securing said clamp in the socket adjustably engaged either with drill rod or with a grief stem, including a bar engaged over the clamp and fastenings for exerting variable pressure on the bar for adjustably seating the clamp in the socket. 80
4. In well drilling apparatus, a drive socket, a drill rod clamp seated in said socket having cylindrical portions for driving engagement with drill rod and grooved for the passage of the ribs or corners of a grief stem and means for securing said clamp in the socket adjustably engaged either with drill rod or with a grief stem, including a bar engaged over the clamp and fastenings for exerting variable pressure on the bar for adjustably seating the clamp in the socket, said bar being of two-part construction consisting of complementary sections engageable laterally over the clamp from opposite sides of the drill rod or grief stem. 85
5. In well drilling apparatus, a rotary table, a sleeve slidably keyed to said table, a drive collet carried by said sleeve having a cylindrical portion for clamping engagement with smooth drill rod and grooved to receive the ribs or corners of a grief stem and means for variably seating said collet in engagement with drill rod or with a grief stem. 90
6. In well drilling apparatus, a rotary table, a sleeve slidably keyed to said table, a drive collet carried by said sleeve having a cylindrical portion for clamping engagement with smooth drill rod and grooved to receive the ribs or corners of a grief stem, means for variably seating said collet in engagement with drill rod or with a grief stem and power mechanism for applying variable lifting or lowering force to the sleeve without interfering with rotation of the same by the rotary table. 95
7. In well drilling apparatus, a supporting socket, a drill rod chuck seated in said socket, hold-down bolts at opposite sides of the socket and a clamp bar for the chuck consisting of complementary bar sections separately engageable over the chuck from opposite sides and having open slots in the ends of the same engageable laterally about the hold-down bolts. 100
8. In well drilling apparatus, a supporting socket, a drill rod chuck seated in said socket, hold-down bolts at opposite sides of the socket and a clamp bar for the chuck consisting of complementary bar sections separately engageable over the chuck from opposite sides and having open slots in the ends of the same engageable laterally about the hold-down bolts, the slotted end portions of the bar sections being oppositely inclined to relatively interlock when engaged about the hold-down bolts. 105
9. In well drilling apparatus, a chuck for gripping engagement with a drill stem, said chuck being shouldered for interlocking engagement with a shouldered grief stem and internally screw threaded to form a companion interlocking screw thread in the drill stem. 110
10. In well drilling apparatus, a chuck for gripping engagement with a drill stem, said chuck being shouldered for interlocking engagement with a shouldered grief stem and internally screw threaded to form a companion interlocking screw thread in the drill stem and a socket for the chuck adapted to force the same into firmer gripping engagement with the drill stem as said chuck screws itself down over the drill stem. 115
11. In well drilling apparatus, a chuck having cylindrical portions for gripping engagement with a drill stem and recessed portions to interlock with a shouldered grief stem, the intermediate cylindrical portions which engage the drill stem being formed with a screw thread and hardened to cut a companion thread in the drill stem when relatively rotated. 120
12. In well drilling apparatus, a chuck having cylindrical portions for gripping engagement with a drill stem and recessed portions to interlock with a shouldered grief stem, the intermediate cylindrical portions which engage the drill stem being formed with a screw thread and hardened to cut a companion thread in the drill stem when relatively rotated, a socket for the chuck and clamp means adjustable to force the chuck seated in said socket. 125
13. In combination with a rotary table, a chuck rotated thereby having cylindrical portions for gripping engagement with a drill stem and shouldered to interlock with a shouldered grief stem, the cylindrical portions of said chuck being screw threaded to form a companion screw thread in drill stem engaged thereby. 130
14. In well drilling apparatus, a rotary table, a socket keyed thereto, a drill stem

- chuck keyed in said socket, means for forcing said chuck to a seat in the socket, a drill stem passing through said chuck and complementary means on the chuck and drill stem for automatically forcing the chuck to its seat in the socket independently of the first means.
15. In well drilling apparatus, a rotary table, a socket keyed thereto, a drill stem 10 chuck keyed in said socket, means for forcing said chuck to a seat in the socket, a drill stem passing through said chuck and complementary means on the chuck and drill stem for automatically forcing the chuck to its seat in the socket independently of the first means, including screw threaded portions on the chuck and complementary screw threads formed on the drill stem.
16. The method of maintaining an effective 20 rotary driving grip on a rotary drill pipe or like substantially cylindrical object, which comprises forming an externally tapered grip member with internal screw threads which will cut their way in the surface of the object and pitched to advance the grip member over the object with the smaller tapered end foremost when said member is turned in the direction in which the object is to be rotated, seating said member in a tapered socket in clamping engagement with the surface of the object and then rotating said socket in the object-turning direction so that slippage between the grip member and object will have the effect of 30 causing the grip member to thread itself over the object into deeper-seated relation in the contracting socket.
17. In well drilling apparatus, a rotary table adapted for passage of the drill pipe therethrough, a downwardly tapered socket 40 carried by said table, a sectional drill pipe grip seated in said socket, a clamp bar consisting of complementary bar sections separately engageable about opposite sides of the drill pipe passing through the table and adapted to force the sections of the grip down into the tapered socket, screw bolts for exerting downward pressure on said bar sections and said bar sections having recessed 45 ends to accommodate the shanks of said bolts.
18. In apparatus for rotarily driving rounded objects, a contracting socket, an object gripping chuck in said socket, clamp means for securing the chuck in the socket and an internal screw way on the chuck for causing the latter upon slippage over the object to cut its own screw threads in the object and thereby advance itself the further into the contracting socket.
19. In means for rotarily driving rounded objects, a contractable chuck, means for contracting the chuck upon an object to be driven and screw thread forming means carried by the chuck for automatically cutting a chuck
- closing screw thread in the object upon relative slippage of the chuck and object.
20. In means for rotarily driving rounded objects, a contracting chuck having an interrupted screw threaded internal gripping surface and a contracting socket for the chuck adapted to force the chuck into firmer gripping engagement with the object upon advancing of the chuck therein by slippage and cutting by the chuck of its own screw threads in the object.
21. As an article of manufacture, a drive collet having an externally conical contractable portion and a drive head at one end, the contractable portion of said collet having a substantially cylindrical interior with screw threads formed in the face of the same and a grief stem receiving grooves cut longitudinally through said screw threaded face.
22. As an article of manufacture, a drive collet having an externally conical contractable portion and a drive head at one end, the contractable portion of said collet having a substantially uninterrupted cylindrical interior with screw threads formed in the face of the same.
23. As an article of manufacture, a downwardly tapered conical drive collet, the bore of said collet tapering toward the upper, larger end of the collet and having a screw thread formed in the upwardly tapering face of the same.
24. In drilling apparatus, a rotary table, a chuck sleeve having a sliding driven engagement therewith, hydraulic feed mechanism connected with said chuck sleeve for raising and lowering the same, a stem engaging chuck carried by the sleeve and means for automatically closing said chuck upon the stem on relative rotative movement between chuck and stem.
25. As an article of manufacture a drive collet having an externally conical contractable portion provided with an interrupted screw thread on the inner wall of the same, the bore of the collet in which the screw threads are formed being tapered in diameter away from the smaller end of the conical portion.
26. In well drilling apparatus, a rotary table, a collet for gripping engagement with a drill pipe, a socket carried by the rotary table for holding said collet in gripping engagement with the drill pipe, clamp means overstanding the end of said collet and adjustable to force the collet to a variable extent into said socket and stop means for limiting the extent to which the collet may be forced into the socket.
27. In well drilling apparatus, a rotary table, a collet for gripping engagement with a drill pipe, a socket carried by the rotary table for holding said collet in gripping engagement with the drill pipe, clamp means overstanding the end of said collet and ad-

justable to force the collet to a variable extent into said socket and stop means for limiting the extent to which the collet may be forced into the socket, said stop means being 5 readily removable to enable the clamp means to force the collet into the socket to the full extent.

28. In well drilling apparatus, a rotary table, a collet for gripping engagement with 10 a drill pipe, a socket carried by the rotary table for holding said collet in gripping engagement with the drill pipe, clamp means overstanding the end of said collet and adjustable to force the collet to a variable extent into said socket, said socket being tapered to contract the collet upon the drill pipe and said collet having internal screw threads to cause said collet to screw itself over the pipe and down into the socket independently of the pressure of the overstanding clamp.

29. In well drilling apparatus, a rotary table having a passage therethrough, a drive sleeve slidingly keyed in said passage, power 25 means for positively raising and lowering said drive sleeve in the table independently of the rotation of the table, a downwardly tapered socket in the upper end of said drive sleeve, a sectional drill pipe grip seated in 30 said socket, a clamp overstanding said sectional grip and securing means for said overstanding clamp operative on relative vertical adjustment of the clamp and drive sleeve to cause the grip to be forced by the clamp 35 down in the tapered socket into holding engagement with drill pipe extending through the drive sleeve.

30. A sectional longitudinally shouldered 40 grief stem united by screw-threaded joints and having plain portions adjoining the screw joints at the ends of the sections, said plain portions of two adjoining sections being of less diameter than the shouldered portions throughout the length across the joint 45 between the shouldered portions of adjacent sections, a chuck having shoulders complementary to the shoulders on the sectional grief stem to thereby interlock therewith, the said non-shouldered portions across the 50 joints in addition to being of continuously less diameter than the shouldered portions of the stem being of greater length than the length of the chuck, so that when said plain portions at the joints of the grief stem are 55 brought into register with the chuck, the grief stem and chuck may be relatively rotated free of the interlocking engagement above referred to, to bring the shoulders on the section at either side of the joint into 60 register and interlocking engagement with the shoulders on the chuck.

31. A sectional longitudinally shouldered 65 grief stem united by screw-threaded joints and having plain portions adjoining the screw joints at the ends of the sections, said

plain portions of two adjoining sections being of less diameter than the shouldered portions throughout the length across the joint between the shouldered portions of adjacent sections, a chuck having shoulders complementary to the shoulders on the sectional grief stem to thereby interlock therewith, the 70 said non-shouldered portions across the joints in addition to being of continuously less diameter than the shouldered portions of the stem being of greater length than the length of the chuck, so that when said plain portions at the joints of the grief stem are 75 brought into register with the chuck, the grief stem and chuck may be relatively rotated free of the interlocking engagement above referred to, to bring the shoulders on the section at either side of the joint into register and interlocking engagement with the shoulders on the chuck, a drive 80 sleeve in which said chuck is mounted, a rotary table in which said drive sleeve is slidely keyed, and power means for raising and lowering the drive sleeve in the table to thereby bring the chuck into position for interlocking engagement with different sections of the grief stem.

32. In well drilling apparatus, a rotary table, a drill pipe drive sleeve having a vertical sliding driven engagement in said rotary table, a tapered socket in the upper end of said drill pipe driving sleeve, drill pipe gripping segments seated in said socket, a clamp overstanding said drill pipe gripping segments and comprising complemental bar sections laterally engageable about the drill pipe passing down through the sleeve, hold-down bolts at opposite sides of the socket on the drive sleeve operating on the complemental bar sections for forcing the pipe gripping segments down in the socket into adjustable engagement with the drill pipe and means for forcing the drill pipe gripping segments to turn with the complemental clamp bars.

In witness whereof, I have hereunto set my hand this 23rd day of January, 1925.

WALDO SHELDON.
